Primary Examiner — Ralf Seifert(74) *Attorney, Agent, or Firm* — Leydig, Voit & Mayer Ltd.(57) **CLAIM**

The ornamental design for a chamber for a diaphragm pump, as shown and described.

DESCRIPTION

FIG. 1 is a front perspective view of a chamber for a diaphragm pump showing the claimed design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and

FIG. 8 is a bottom view thereof.

FIG. 9 is a front perspective view of the chamber for the diaphragm pump shown in FIG. 1 shown in relation to a second chamber for the diaphragm pump;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and

FIG. 16 is a bottom view thereof.

FIG. 17 is a front perspective view of a diaphragm pump that includes a chamber for the diaphragm pump as shown in FIG. 1;

FIG. 18 is a front view thereof;

FIG. 19 is a rear view thereof;

FIG. 20 is a right side view thereof;

FIG. 21 is a left side view thereof;

FIG. 22 is a top view thereof; and,

FIG. 23 is a bottom view thereof.

The broken line representations are for purposes of illustration only and form no part of the claimed design.
